UNITED STATES PATENT OFFICE

THOMS F. SAMUEL AND JOSEPH H. WOLCOTT, OF BOSTON, GEORGIA.

COMBINED TOBACCO AND MATCH BOX.

1,138,980.

Specification of Letters Patent.

Patented May 11, 1915.

Application filed May 10, 1913. Serial No. 766,770.

To all whom it may concern:

Be it known that we, THOMS F. SAMUEL and JOSEPH H. WOLCOTT, citizens of the United States, residing at Boston, in the 5 county of Thomas and State of Georgia, have invented new and useful Improvements in Combined Tobacco and Match Boxes, of which the following is a specification.

An object of the invention is to provide 10 a combined tobacco and match box.

The invention embodies, among other features, the provision of a match box in which matches can be individually removed therefrom and also comprehends a tobacco box 15 for use in connection with the match box and which, when attached thereto, constitutes a part thereof.

In the further disclosure of the invention reference is to be had to the accompanying 20 drawings, constituting a part of this specification, in which similar characters of reference denote corresponding parts in all the views, and in which:

Figure 1 is a perspective view of the combined tobacco box and match box, parts being broken away to disclose the underlying structure; Fig. 2 is a vertical transverse sectional view taken through the operating mechanism of the match box; and Fig. 3 is 30 a vertical transverse sectional view taken through the interior of the match box.

Referring more particularly to the views, we disclose a casing 10 divided by a vertical partition 11 into a plurality of compartments 12 and 13, a lid 14 being provided for the casing 10 to close the compartment 12, the said lid preferably being arranged for sliding engagement with the casing 10, as shown and provided in order that a number 35 of matches 15 can be readily arranged in bulk within the compartment 12, an inclined floor 16 being arranged in the compartment 12 and upon which the matches are adapted to be received so that they will 40 gravitate toward a longitudinal slot 17 formed in the front wall of the compartment 12 as shown.

A roller 18 is journaled in the compartment 12 to normally close the slot 17, the 50 said roller being provided with a longitudinal groove 19 of sufficient width to accommodate a single match, with the said groove normally out of registration with the slot 17 and lying within the compartment 12 55 so that when the matches 15 are arranged therein and gravitate down the inclined floor

16, one of the matches will be received in the groove 19 of the roller 18. The roller 18 at one end thereof carries a stud 20 projecting through the partition 11 and keyed 60 on the projecting end of the stud 20 is a disk 21 having secured thereto one end of a contractile spring 22 arranged in the compartment 13 and having the other end thereof secured to a wall of the compartment. A 65 lever 23 has pivotal connection with the disk 21 and extends upwardly through an opening 24 in the top of the compartment 13, the said lever terminating in a finger piece 25 normally lying flush with the top of the 70 compartment 13 and constituting a portion of the wall thereof.

Now it will be readily apparent that when a downward pressure is exerted on the finger piece 25 rotation will be imparted to the 75 disk 21 and which will be actuated against the contractile action of the spring 22, thus imparting rotation to the roller 18 to move the groove 19 into registration with the slot 17 so that the single match contained in the 80 groove will fall through the slot and exteriorly of the compartment 12 containing the matches. When the downward pressure on the finger piece 25 is released the action of the spring 22 will return the roller 18 to normal 85 position so that another match in the compartment 12 will gravitate into the groove of the roller, the roller when in normal position being adapted to close the slot 17 to prevent the accidental displacement of 90 matches from the compartment 12, as will be readily understood.

The rear face 26 of the casing 10 terminates at the upper and lower edges in longitudinal beads 27 forming guideways for 95 a tobacco casing 28 and which has edges 29 thereof grooved to receive the beads 27 when the casing 28 is engaged with the casing 10 so that the tobacco casing 28 can be slid into engagement with the casing 10 and closed 100 by the rear face 26 of the casing 10 forming a wall or cover for the tobacco casing 28, as will be readily apparent by referring to the views. When it is desired to remove tobacco from the tobacco casing 28 it is only 105 necessary to slide the same slightly outwardly at one end of the casing 10 and it will be further understood that the match box forming a part of this application can be used independently of the tobacco casing 110 or in conjunction therewith, as described.

Having thus described our invention, we claim:

In a match box, the combination with a casing, of a partition forming a plurality of compartments in the casing, an inclined floor in one of the compartments and terminating at one end adjacent a longitudinal slot in the casing, a roller mounted to turn in the first mentioned compartment and lying adjacent the lower end of the inclined floor, with the said roller normally closing the said slot and provided with a longitudinal groove adapted to register with the slot for ejecting matches through the slot, the said matches being contained on the said inclined floor, a stud projecting from one end of the roller and into the other compartment, a disk carried by the stud, a contractile spring having connection with the disk and

with the casing for normally holding the 20 roller in normal position to close the slot, a lever having pivotal connection with the said disk for imparting rotation to the roller to move the groove thereof into registration with the slot, and a finger piece projecting through an opening in a wall of the second compartment, with the said finger piece carried by the said lever and normally lying flush with the wall of the second compartment to constitute a portion thereof. 30

In testimony whereof we affix our signatures in presence of two witnesses.

THOMS F. SAMUEL.
JOSEPH H. WOLCOTT.
